UNITED STATES PATENT OFFICE.

HARVEY C. NEWCOM, OF GREGORY, SOUTH DAKOTA.

CRANK HANDLE.

Application filed March 20, 1922. Serial No. 545,322.

To all whom it may concern:

Be it known that I, HARVEY C. NEWCOM, a citizen of the United States, residing at Gregory, in the county of Gregory and State 5 of South Dakota, have invented new and useful Improvements in Crank Handles, of which the following is a specification.

In carrying out the present invention it is my purpose to provide a crank handle 10 which will be found especially useful in connection with the cranks used on hand operated churning, washing machines, automobiles, etc., and wherein the handle will be connected with the crank arm that such 15 handle may be readily and conveniently swung to active and inactive positions whenever desired.

It is also my purpose to improve and simplify the general construction of crank 20 handles of the class described and to provide a crank handle which may be readily and quickly attached to the crank arm, so that in the event of the breaking of one crank handle a new one may be substituted there- 25 for.

Furthermore, I aim to provide a crank handle which may be manufactured and marketed at small cost and which will embody comparatively few parts and these so 30 arranged and correlated as to reduce the possibility of derangement to a minimum.

With the above recited objects in view, and others of a similar nature, the invention resides in the construction, combination 35 and arrangement of parts set forth in and falling within the scope of the appended claims.

In the accompanying drawings:

Figure 1 is a view in side elevation of a 40 crank handle constructed in accordance with my invention, the same being shown as applied to the lower end of a crank arm.

Figure 2 is a longitudinal sectional view therethrough showing the crank handle in 45 active position.

Figure 3 is a similar view showing the handle in inactive position.

Figure 4 is a sectional view on the line 4-4 of Figure 1.

Figure 5 is a sectional view on the line 50 5-5 of Figure 1.

Referring now to the drawings in detail, 1 designates the handle end portion of the crank arm. In accordance with my invention 55 the lower end of the crank arm 1 is formed with a transverse bore 2. Extend-

ing through the bore 2 is a threaded shank 3 and threaded upon one end of the shank 3 is a nut 4. The other end of the shank 3 projects beyond the crank arm 1 and is bifurcated to provide forked arms 5. Surrounding the bifurcated end of the shank is a casting or housing 6 formed with a longitudinal slot 7 and the outer end of the casting is formed with an opening 8 contiguous to the slot 7.

9 designates a hand grip which, in the present instance, comprises a shank 10, one end of which is flattened, as at 11, and extends through the opening 8 and into the 70 space between the bifurcated arms 5. This flattened end of the shank is pivoted to the arms 5 by means of a pivot bolt 12. In the present instance the pivot bolt 12 extends through the opposite side walls of the housing 6 and cooperates with the nut 4 to hold the shank 2 securely to the lower end of the crank arm 1, as clearly illustrated in Figures 1, 2 and 3 of the drawings. Encircling the shank 10 beyond the housing 6 is a sleeve 80 13 having its outer end enlarged, as at 14, and formed with a recess 15 in which is seated the head 16 on the shank 10, the head 16 acting to prevent accidental detachment of the sleeve from the shank.

The top wall of the housing 6 adjacent to the opening 8 in the outer end of such housing is formed with a slot 17 and pivoted within the slot 17 scissors-fashion are levers 18. The inner ends of the levers 18, that is 90 to say, the ends of the levers within the housing 6, are formed to provide clamping jaws 19, while interposed between the outer ends of the levers and connected thereto is a coiled expansion spring 20 that acts to 95 hold the jaws in closed position.

In practice, when it is desired to swing the crank handle to active position, as shown in Figure 2, from the position shown in Figure 3, the shank 10 is swung upwardly 100 through the slot 7 and into the opening 8, and in this position the shank 10 of the hand grip is at right angles to the crank arm 1. In the upward movement of the shank 10 the shank enters the jaws 19, as clearly 105 shown in Figure 4 of the drawings, and is effectively clamped by the jaws 19 under the action of the spring 20, so that the hand grip will be maintained in active or cranking position. To render the hand grip inactive the latter is pushed downwardly, 110 thereby disengaging the jaws 19 and gravi-

tates to the position shown in Figure 3 of the drawings.

In the event that the shank 10 does not leave the jaws 19 when a downward pressure is exerted on the hand grip the outer ends of the levers 18 may be swung together against the action of the spring 20, thereby assuring the release of the hand grip.

I have entered into a detailed description 10 of the construction and relative arrangement of parts embraced in the present and preferred embodiment of my invention with a view to imparting a full, clear and exact understanding of the said embodiment. I 15 do not desire, however, to be understood as confining myself to the said specific construction and relative arrangement of parts, inasmuch as in the future practice of my invention such changes or modifications may 20 be made as fairly fall within the scope of my invention as defined by my appended claims.

Having thus described the invention, what is claimed as new, is:—

25 1. The combination with a crank arm having an opening formed in the lower end thereof, of a shank extending through said opening and secured therein and having one end bifurcated to provide forked arms arranged at right angles to said crank arm, a hand grip embodying a shank having one end pivoted between said arms, a sleeve on said shank beyond said arms, a housing surrounding said bifurcated arms and formed 30 with a slot in its lower portion and opening in its outer end through which said hand grip may be swung to active and inactive positions, and means carried by said housing and engageable with said shank to hold 35 said hand grip in active position.

40 2. The combination with a crank arm having an opening formed in the lower end thereof, of a shank extending through said opening and secured therein and having one end bifurcated to provide forked arms arranged at right angles to said crank arm, a hand grip embodying a shank having one end pivoted between said arms, a sleeve on said shank beyond said arms, a housing surrounding said bifurcated arms and formed 45 with a slot in its lower portion and opening 50 in its outer end through which said hand grip may be swung to active and inactive positions, and means carried by said housing and engageable with said shank to hold said hand grip in active position.

in its outer end through which said hand grip may be swung to active and inactive positions, said housing having the upper surface thereof formed with a slot contiguous to the opening in the outer end thereof and jaws pivoted within said slot and engageable with said shank to hold said hand grip in active position. 55

3. The combination with a crank arm having an opening formed in the lower end thereof, of a shank extending through said opening and secured therein and having one end bifurcated to provide forked arms arranged at right angles to said crank arm, a hand grip embodying a shank having one end pivoted between said arms, a sleeve on said shank beyond said arms, a housing surrounding said bifurcated arms and formed with a slot in its lower portion and opening 60 in its outer end through which said hand grip may be swung to active and inactive positions, said housing having the upper surface thereof formed with a slot contiguous to the opening in the outer end thereof and jaws pivoted within said slot and engageable with said shank to hold said hand grip in active position. 65

4. The combination with a crank arm having an opening formed in the lower end thereof, of a shank extending through said opening and secured therein and having one end bifurcated to provide forked arms arranged at right angles to said crank arm, a hand grip embodying a shank having one end pivoted between said arms, a sleeve on said shank beyond said arms, a housing surrounding said bifurcated arms and formed 70 with a slot in its lower portion and opening in its outer end through which said hand grip may be swung to active and inactive positions, said housing having the upper surface thereof formed with a slot contiguous to the opening in the outer end thereof and jaws pivoted within said slot and engageable with said shank to hold said hand grip in active position. 75

5. The combination with a crank arm having an opening formed in the lower end thereof, of a shank extending through said opening and secured therein and having one end bifurcated to provide forked arms arranged at right angles to said crank arm, a hand grip embodying a shank having one end pivoted between said arms, a sleeve on said shank beyond said arms, a housing surrounding said bifurcated arms and formed 80 with a slot in its lower portion and an opening in its outer end through which said hand grip may be swung to active and inactive positions, means carried by said housing and engageable with said shank to hold said hand grip in active position, and a pivot bolt extending through said housing, bifurcated arms and the inner ends of said shank and acting to hold said housing in proper position and said shank between said arms. 85

In testimony whereof I affix my signature.

HARVEY C. NEWCOM.
